Patented Jan. 7, 1902.

F. D. SWANEY.

SELF CLOSING FIREPROOF WINDOW.

(Application filed Feb. 12, 1900.)

(No Model.)

THE NORRIS PETERS CO., PHOTO-LITHO., WASHINGTON, D. C.

UNITED STATES PATENT OFFICE.

FLETCHER D. SWANEY, OF KANSAS CITY, KANSAS, ASSIGNOR TO JOHN A. RITZLER, OF KANSAS CITY, MISSOURI.

SELF-CLOSING FIREPROOF WINDOW.

SPECIFICATION forming part of Letters Patent No. 690,535, dated January 7, 1902.

Application filed February 12, 1900. Serial No. 4,898. (No model.)

To all whom it may concern:

Be it known that I, FLETCHER D. SWANEY, a citizen of the United States, residing at Kansas City, Wyandotte county, Kansas, have invented a new and useful Self-Closing Fireproof Window, of which the following is a specification.

My invention relates to self-closing fireproof windows, and more particularly to that class which embody a connection destructible when exposed to flame or a certain degree of heat for the purpose of relieving the lower sash of the counterbalance-weights or imposing upon the upper sash supplemental weights in order to effect the quick and reliable closing operation of the sash.

The object of the invention is to produce a self-closing window of the character described thoroughly practical and at the same time simple, strong, durable, and comparatively cheap of construction.

To this end the invention further consists in certain novel and peculiar features of construction and organization, as hereinafter described, and pointed out in the appended claims, and while the drawings show and the specification describes the preferred embodiment of the invention it is to be understood that I reserve the right to make such changes in the detail construction, form, arrangement, or proportion of the parts as do not involve a departure from the spirit and scope or sacrifice any of the advantages of the invention as outlined by said claims.

In order that the invention may be fully understood, reference is to be had to the accompanying drawings, in which—

Figure 1 is a view from the outer side, partly in elevation and partly in vertical section on the line I I of Fig. 2, of a self-closing fireproof window embodying my invention, the same being shown in sections in order that the parts shall appear on a large scale and in proper proportion to each other. Fig. 2 is a vertical section, on the same scale, taken on the line II II of Fig. 1. Fig. 3 is a vertical section taken on the line III III of Fig. 1. Fig. 4 is a horizontal section, on the same scale, taken on line IV IV of Fig. 1. Fig. 5 is a detail vertical section illustrating my preferred

method for securing the lower ends of the pocket-strips in place.

Referring now to the drawings, wherein like reference-numerals designate corresponding parts, 1 designates the subsill of the window-casing, adapted to be secured upon the sill of a window-opening in the customary manner, 2 the top of the casing, and 3 the vertical sides connecting the top with the subsill, the whole being formed of galvanized iron or other sheet metal and of hollow construction. The inner sides of the casing are formed with the parallel vertical strips 4, 5, and 6, the two first named providing grooves 7, in which the upper or outer sash is adapted to operate, and the two last named grooves 8 for the lower sash.

In order to facilitate the insertion of the counterbalance-weights for the upper or outer sash, the base of the lower half of grooves 7 is formed with openings 9, (see Figs. 1 and 5,) said openings being normally closed by pocket-strips 10, fitting snugly in said grooves and of corresponding form in end view. (See Fig. 4.) These strips are of such length that their upper ends are always overlapped by the upper sash and their lower ends are formed with inwardly-projecting flanges 11. Flanges 12 projecting upward from the subsills are riveted to the angle-plates 13, on which are seated the lower ends of said strips, and the strips are maintained in this relation by hooking the inner ends of said angle-plates, as at 14, upon said strip-flanges 11, as shown clearly in Fig. 5.

15 designates the upper sash of the window, the same being adapted to reciprocate in the customary manner in the grooves 7, and by lapping the pocket-strips 10, as explained, prevent them from swinging inward at their upper ends. This sash is preferably formed of sheet metal, and is of hollow construction, and is provided with what is known as "wire-glass" 16, which retains its position, though cracking in every direction under the intense heat of a fire.

The sash is formed in its edges with the side grooves 17 and at its upper end with a horizontal groove 18 and is also provided with a bolt-hole 19. Secured to its under

side and projecting therefrom into the grooves 7 are hooks 20, and attached to said hooks are steel tapes 21, which extend through castings 22, secured to the casing and registering with openings therein, said tapes extending over pulleys 23, journaled in said castings and having attached to their outer ends the counterbalance-weights 24, arranged centrally of the hollow sides 3 of the casing. The weights shown are of the usual type and need no particular description, and after the window is secured in the building, as hereinbefore stated, are adapted to be passed through openings 9 and hooked to the lower ends of said tapes. After said weights are thus secured, the upper ends of said strips 10 are slipped into position, and plates 12 are hooked to the flanges 11, as hereinbefore explained. Vertically above the pulley-carrying casting 22 is a similar casting 25, provided likewise with a pulley 26, projecting into the side grooves of sash 15 and into the hollow sides 3 of the casing and extending through the casting, and over said pulleys 26 are the flexible cables 27, preferably of combustible or inflammable material, such as tarred rope. Said cables occupy groove 18 in the upper edge of the sash and are connected together by the fusible connection 28, such connection being adapted to fuse under a heat of about 120° Fahrenheit. A pair of yokes 29, occupying the hollow sides 3 of the casing, are secured pendently from cables 27, and mounted upon said yokes are the supplemental weights 30, made in sections by preference in order to be more readily adapted to sashes of different weights, and said weights are preferably secured reliably upon the yokes by bending outward the lower ends of the latter, as at 31, though this particular construction is unimportant. The weights are provided with vertical passages 32, through which extend the tapes 21, the principal object of this construction being to produce as simple and compact a construction as possible, though it is clear that the tapes will to a certain extent act as a guide for the supplemental weights and insure their striking the upper ends of the counterbalance-weights 24 a square blow. It is obvious, however, that said weights may be otherwise guided, if desired, though in fact if arranged vertically above the counterbalance-weights 55 they are bound to strike the latter should they fall by reason of the combustible cable burning in two or the connection 28 fusing, as will be readily understood. When the upper sash is closed, the weights 24 and 30 and their connected parts are disposed as shown in Fig. 1. When said sash is lowered, it does not disturb the position of the supplemental weights and their connected parts in the least, but simply raises the counterbalance-weights 24 a corresponding distance, the lowering of the sash of course exposing to view and to the action of flames or heat the com-

bustible and fusible connection at the upper end of the casing and now above the groove 18 in the upper end of said sash. 70

Assuming now that a fire breaks out and that heat fuses connection 28 or flame burns connection 27 in two, it will be apparent that the supplemental weights are released and falling strike the counterbalance-weights, 75 and by thus increasing the weight on the latter to a degree proportionate to the weight of the supplemental weights and to the distance which they fall positively and reliably re-elevate and close said sash. 80

33 designates the lower or inner sash of the window, the same being of precisely the same construction as sash 15, except that the former is provided with a groove 34 (corresponding to groove 18) in its lower end. This sash 85 is adapted to reciprocate in the customary manner in the inner groove 8, and it is provided centrally of groove 34 with a fusible part 35, connecting the inner ends of combustible cables 36, attached at their outer 90 ends, as at 37, (see dotted lines,) or in any other suitable manner, by steel tapes 38, which extend up through the side grooves of the lower sash and the grooves 8 and through the castings 39, secured to the casing at a suitable height, preferably by the side of castings 22. Said tapes also extend over pulleys 40, mounted in said castings in a manner similar to pulleys 23, and are attached to counterbalance-weights 41 of the usual or any preferred 100 construction, said weights occupying their elevated position (see Fig. 3) when the sash is closed and adapted as the sash rises to descend in the customary manner and hold it at the desired point of adjustment. When 105 said sash is elevated, the combustible and fusible connection in the groove in the lower edge of the sash is exposed to heat and the flame in order to insure the quick and positive separation of the weights 41 from the 110 sash, the result of which is that the sash by force of gravity closes, the weights falling to the bottom of the casing. 115

In order to facilitate arrangement of said weights in the hollow sides 3 of the casing, 115 the lower halves of the grooves 8 of the latter are provided with openings 9, closed by strips 10, as hereinbefore particularly described and shown with relation to grooves 7, the construction being shown with the latter principally for convenience of illustration and to avoid the making of superfluous drawings. 120

For convenience in attaching the supplemental weights after the window has been secured properly in the building the inner face of each side 3 of the casing is formed with an opening 42, through which the weights and one's arm may be inserted, it being of course understood that the supplemental weights 130 should be fitted telescopically upon the tapes 21 by threading the latter through the weights before the counterbalance-weights 24 are secured to said tapes. Through the same open-

ing 42 the weights 41 may be inserted, though as said weights will vary materially in length, accordingly as the sash is of heavy or light construction, I prefer to introduce them 5 through the openings 9 of groove 8, as hereinbefore explained. The opening 42 is preferably closed by means of a plate 43, secured in position in any suitable manner.

The windows are fastened, preferably, by 10 means of a spring-catch 44, secured to the top rail of the lower sash and having its bolt adapted to automatically engage the opening 19 of the lower rail of the upper sash. (See Figs. 1 and 2.)

15 As the various operations of the parts have been explained in detail it is believed unnecessary to recapitulate, and it is apparent that I have produced an invention possessing the features of advantage enumerated as desirable in the statement of invention.

Having thus described the invention, what I claim as new, and desire to secure by Letters Patent, is—

1. In a self-closing window, a sash provided 25 with a horizontal groove, and a destructible weighted connection extending through said groove protected when the sash is closed, but exposed to the direct action of heat and flame when the sash is open, substantially as de- 30 scribed.

2. In a self-closing window, a casing, a counterbalanced sash fitting in the casing and provided with a horizontal groove, a connection extending through said groove, protected 35 when the sash is closed, but exposed to the direct action of heat and flame when the sash is opened, and an independent power, adapted on the parting of said connection to effect the closing of said counterbalanced sash, sub- 40 stantially as described.

3. In a self-closing window, a casing, a grooved sash therein, a counterbalance-weight connected to the sash, a supplemental weight, and a connection extending through the 45 groove of the sash protected when the latter

is closed, but exposed to the action of heat or flame when it is open, and arranged to part or break under the action of heat or flame and impose the burden of the supplemental weight on the sash and thereby close the same, 50 substantially as described.

4. In a self-closing window, a casing, a grooved sash, counterbalance-weights connected thereto, supplemental weights adapted to descend and strike the counterbalance-weights, and a connection adapted to part under the action of heat or flame extending through the groove of the sash for supporting said supplemental weights normally above and out of contact with the counterbalance-weights, and exposed to the direct action of heat or flame when the sash is opened, substantially as described. 55

5. In a self-closing window, a casing provided with hollow sides, a sash mounted reciprocally therein, and provided with side grooves and a horizontal groove, guide-pulleys projecting into the hollow sides of the casing and said side grooves of the sash, counterbalance-weights in said hollow casing 70 sides, non-combustible tapes extending over said pulleys and connecting the sash and counterbalance-weights, supplemental weights mounted in said casing sides and upon the tapes therein, and a suitably-guided connection adapted to part under the action of heat or flame, supporting said supplemental weights normally above and out of contact with the counterbalance-weights, extending through said horizontal groove and protected 80 when the sash is closed, but when the sash is opened exposed to the direct action of heat or flame, substantially as described. 75

In testimony whereof I affix my signature in the presence of two witnesses.

FLETCHER D. SWANEY.
